UNITED STATES PATENT OFFICE.

WILLIAM F. LOTT, OF NEW YORK, N. Y.

DESIGN FOR AN ATHLETIC SHIRT.

43,765.

Specification for Design.

Patented Apr. 1, 1913.

Application filed June 29, 1911. Serial No. 636,132. Term of patent 7 years.

To all whom it may concern:

Be it known that I, WILLIAM F. LOTT, a citizen of the United States, residing in the borough of Brooklyn, city of New York, in the county of Kings and State of New York, have invented a certain new, original, and ornamental Design for Athletic Shirts, of which the following is a specification, reference being had therein to the accompanying drawings, forming part thereof.

Figure 1 is a front view of an athletic shirt showing my design. Fig. 2 is a rear view of the same.

My design includes lines extending downward from the lower portions of the arm holes and converging and meeting, or of substantially V-shape, these lines appearing both on the front and back of the shirt, the shirt having enlarged arm holes and no sleeves.

I claim:

The ornamental design for an athletic shirt, as shown and described.

WILLIAM F. LOTT.
